(57) **CLAIM**

The ornamental design for a ladder safety step as shown and described.

DESCRIPTION

FIG. 1 is a perspective view of a ladder safety step showing the design;

FIG. 2 is a back view thereof;

FIG. 3 is a front view thereof;

FIG. 4 is a first side view thereof;

FIG. 5 is a second side view thereof; and,

FIG. 6 is a top view thereof.

The broken lines shown in the figures are for the purpose of illustrating portions of the forklift truck and form no part of the claim.
